UNITED STATES PATENT OFFICE.

GEORGE W. DONNING, OF STAMFORD, CONNECTICUT.

INTERNAL-COMBUSTION ENGINE.

1,237,311.

Specification of Letters Patent. Patented Aug. 21, 1917.

Application filed October 21, 1911. Serial No. 655,930.

To all whom it may concern:

Be it known that GEORGE W. DONNING, a citizen of the United States, and residing at Stamford, in the county of Fairfield and

5 State of Connecticut, has invented certain new and useful Improvements in Internal-Combustion Engines, of which the following is a specification, reference being had therein to the accompanying drawing.

10 This invention relates to internal combustion engines, and, more particularly, to the two-cycle type thereof.

The primary object of the invention is to construct an engine which embodies all of 15 the desirable features of the two and four-cycle engines and from which are omitted the undesirable and objectionable features of each of these types of engines. In such an improved form of engine, I have turned 20 to advantage certain of the features which heretofore have worked to disadvantage, and I have thereby provided an engine of great simplicity, increased power and efficiency, and enlarged capacity to produce a maximum 25 of results with a minimum loss of power; moreover, in such an engine I am enabled to economize on the fuel necessary to drive the same; to reduce the weight of the structure per horse-power produced, and to 30 obtain an impulse at each and every revolution of the crank-shaft, etc.

Another object is to construct an engine that will have its suction-stroke begin during the exhaust and continue until after the 35 exhaust ceases; likewise, a compression-stroke occurring practically simultaneously, with the work-stroke.

Another object is to construct the engine with a crank-shaft which will be common to 40 the piston and to the valves of the engine, thus dispensing with a separate shaft or like separate instrumentality for operating the valves.

Another object is to compress a suitable 45 medium by means of the piston during its work-stroke, part of which medium is utilized to accelerate the return of said piston during the exhaust-stroke.

Another object is to construct an engine 50 that shall be "fool-proof," and be readily understood, and include comparatively few parts.

Another object is to avoid effecting work, 55 suction and compression-strokes in a common chamber and, also, a compression stroke in the firing-chamber.

Another object is to maintain, in a reservoir, compressed mixture, and thereby provide a medium to facilitate the starting of 60 the motor.

With these and other objects in view, the invention resides, in one aspect, in a cylinder, a piston working therein, explosion and compression chambers at opposite ends of the cylinder, and one or more auxiliary 65 chambers provided at the end of the cylinder opposite to that at which the explosion is effected and communicating with both of said chambers.

The invention consists, also, in another 70 aspect, in a cylinder provided with explosion and compression-chambers at opposite ends of said cylinder, a piston moving in said cylinder, and auxiliary chambers for the explosive mixture disposed contiguous to 75 said compression-chamber.

The invention further consists, in a still 80 different aspect, in an engine constructed as specified and provided with a system of valves and valve-operating mechanisms, the latter deriving operation from positively actuated parts of the engine and timed to produce accurate and predetermined results.

The invention further consists in valve-mechanism positively operated by a shaft 85 common to such mechanism and to the piston of the engine.

The invention resides, also, in the novel 90 form and aggroupment of the parts, as hereinafter fully described and claimed.

In the accompanying drawings, I have 95 illustrated but one form of embodiment of my invention; but it is to be understood and I hereby assert that the principles and salient features of my invention are capable of being embodied in other forms of structures and still be within the spirit of the invention.

In these drawings:

Figure 1 is a view in sectional elevation 100 illustrating my invention as embodied in an engine comprising, in this instance, three cylinders;

Fig. 1^a is a fragmentary view illustrating one of the valves, etc., for controlling the 105 passage of the mixture;

Fig. 2 is a vertical section on the line 2—2, Fig. 1;

Fig. 3 is a view in elevation, some of the 110 parts being shown in section, and showing particularly a direct valve-operating mechanism;

Fig. 4 is a similar view of the opposite side of the cylinder;

Fig. 5 is a view, partly in plan, and partly in horizontal section, the section being taken on line 5—5, Fig. 1;

Fig. 6 is a sectional view of one preferred form of valve which I may employ in the engine;

Fig. 7 is a fragmentary view of a washer 10 adapted to encircle the stem of the valve illustrated in Fig. 6;

Fig. 8 is a view of a valve confining plate; and

Fig. 9 is a diagrammatic view showing 15 the approximate periods of ignition operation and inactivity of the valves during the work and exhaust-strokes, respectively, of the piston.

Referring to the drawings, 1 designates a 20 cylinder which, in this instance, includes a body-portion 2, a cap-portion 3, and a crank-case portion 4. It is to be understood, however, that these several portions may, if desired, be integral; or, on the other hand, may 25 comprise a greater number of sections.

The body-portion 2 is preferably provided with an annular space 5 adapted to house water or any other cooling medium. The cap-portion is similarly provided with cooling-channels 6 adapted to contain a cooling medium, such as water. The channels or spaces 5 and 6 are adapted to have communication, as through the ports 7, Fig. 2.

As shown, by way of example in Fig. 2, 35 the upper end of the body-portion 2 is provided with an annular projection 8 adapted to fit into a corresponding incut 9 whereby interlocking of these two portions is effected. As usual, they are also secured together, as 40 by screws 10. Intermediate of the body-portion 2 and the portion 4 is an annular section 11 provided at suitable points with apertures 12 adapted to be covered by plates or covers 13, suitably secured, as by screws 14. By the provision of these plates, access 45 to the interior of the cylinder adjacent to the crank-shaft, etc., is permitted.

The portion 11 is provided with the interlocking means 15 similar to that already described in connection with the cap-portion, and by these means said section 11 is interlocked with the body-portion 2 and with the crank-case portion 4, and whereby the parts 55 are rigidly secured together and leakage prevented.

The crank-case portion 4 is preferably divided, as by the partition 16, whereby a plurality of auxiliary chambers 17 and 18 are provided. Both of these chambers are storage-chambers, that marked 17 being adapted to house a body of oil and from which the various parts of the engine are lubricated in a manner hereinafter to be more fully explained. The other chamber 18 is adapted 65 to receive and store the compressed mixture,

as will be more fully set forth hereinafter. It will be understood that instead of dividing by the partition 16, there may be one storage-chamber adapted to house oil and constitute a source of supply of lubricant 70 for the engine. Similarly, this single chamber could be utilized for housing the compressed mixture.

Working in the cylinder is a piston 19 provided as usual with circumferential expansion rings 20. The piston-head is in this instance shown as hollow, and with a removable top-plate 21. It will be understood, however, that the head may be solid.

Pivoted depending from the piston is a 80 pitman 22 pivoted at its lower end to a crank-shaft 23, the crank-shaft being provided with two pendant counterbalancing and space-filling portions 24.

The piston divides the cylinder into two 85 chambers, namely, the explosion-chamber 25 and the compression-chamber 26. The compression-chamber is of reduced proportions and the crank of the shaft is of such dimensions as to nearly fill said chamber, as is shown 90 in Fig. 1, the object of this construction being to utilize the piston to effect as high a degree of compression as possible during a part of the rotative movement of the crank-shaft while the piston is approaching its 95 lowermost position. The enlarged portions 24 have a rotative movement around the axis of the crank-shaft and in order that the piston 19 may approach as nearly as possible the said axis, the pitman 22 is only 100 of that length which will permit the longest movement of the piston toward said axis. To permit the enlarged portion 24 to pass the head when the piston is in its extreme lower position, said piston is provided with 105 an arcuate clearance space 27, as shown in Fig. 2.

I will provide the motor with any well-known igniting system, preferably one that is equipped with a spark-timer, so that the 110 same may be advanced or retarded at will.

This may be of any preferred form and as its operation is well-known, I have not shown the same. Likewise, I employ a standard carbureter having preferably an automatic 115 valve which is operated in one direction by vacuum created within the compression-chamber and in the opposite direction by the compression-stroke, as is well understood. This may, also, be of any preferred form and 120 as it forms no part of my invention, I have not deemed it necessary to illustrate the same herein. Likewise, a standard system of oil distribution and mechanism therefor, additional to that herein disclosed, may be provided for lubricating the various movable parts of the structure. As this may, also, be 125 of any preferred type, and as the same forms no part of my invention, I have not deemed it necessary to disclose the same herein.

130

Similarly, any preferred system of cooling and water-circulating mechanism may be employed; and, as these form no part of my invention, I have not deemed it essential to disclose the same herein.

The partition 16 is provided with a central bore 28 terminating at its lower end with a drain-cock 29. By this means, any surplus oil, etc., may be withdrawn from the compression-chamber 26.

Likewise cocks 30 and 31 are provided at the lower portions of the oil and storage-chambers, 17 and 18, respectively; and, by this means, the contents of such chambers, etc., may be removed when desired.

To provide a means of communication between the storage-chamber 18 and the explosion-chamber 25, a channel 32 is formed in the wall of the cylinder. I prefer to form this channel in the wall, first, because it simplifies the construction; secondly, because it avoids the necessity of providing a pipe and connections outside of the cylinder; and, thirdly, because the mixture, as it passes from the storage-chamber to the explosion-chamber, is heated more or less by reason of the channel being in proximity to the firing-chamber, etc. Such heating, however, is of course more or less controlled by reason of the fact that said channel is also in proximity to the cooling-channels or spaces.

Means are provided for controlling the passage of the mixture from the compression-chamber 26 to the storage-chamber 18, and, then, from said last-mentioned chamber to the explosion-chamber. These means preferably comprise, in the first instance, a positively-actuated valve 33 of the form shown in Fig. 6. As therein shown, this valve includes a cylindrical body-portion 33^a preferably hollow to provide a chamber 33^b, said body-portion being provided with an elongated aperture 33^c and a stem 34.

The exterior wall of the valve is provided with one or more circumferential grooves in which expansion-rings 35 are held and which prevent leakage and take up all wear. This valve is designed to control a port 36 in the

wall 26^a between the compression-chamber and the storage-chamber. As shown, the walls of this port are somewhat elongated to provide a bearing-surface for the aforementioned body-portion of the valve, and at its inner end is provided with an annular shoulder 36^a to limit the movement of the valve in one direction and to provide a means for preventing leakage. This valve preferably has a rotative movement produced in the following manner: The stem 34 has connected to its outer end a crank-arm 37 provided with a small roller 38 adapted to traverse a cam-groove 39 formed in a cam-disk 40 secured on the main crank-shaft 23. By having the two walls, form-

ing the groove 39, the roller 38, and, thereby, the crank-arm and valve-stem, are guided and positively actuated in their several directions of movement without lost motion or the like. Encircling the stem 34 in front of the outer end of the body-portion of the valve is a resilient washer 41 (Figs. 6 and 7) adapted to maintain the valve firmly seated against the shoulder 36^a. The valve and washer are removably retained in the port by a retaining-plate 42 (Fig. 8) secured to the outside wall of the cylinder, as shown.

As shown in Fig. 1^a, the channel 32 at its lower end is formed at one side of the valved port 36, and forms a direct means of communication between the storage-chamber 18 and the explosion-chamber 25. The valve 33 therefore does not operate to control the passage of the compressed mixture through the channel 32; but such control is by a second valve 43 of form similar to the valve 33, and operating in the same manner, by means of a stem 44 extending from it and provided at its lower end with a link 45 pivoted on a part of the cylinder and carrying a roller 46 adapted to traverse a second cam-groove 47 in the cam-disk 40. As will presently be explained, the timing of the valves is relatively different. One of the plates 42 is arranged in conjunction with the valve 43. In each instance where these plates are employed, they are preferably secured to the outside of the cylinder and are removable, replaceable and interchangeable, and are so constructed that any possible leakage, should the same occur, will become apparent around the edges of the orifice 42^a in the plate. By reason of this fact, one can always readily determine whether a valve is leaking and if so which one of the plurality employed. Then, a quick repair is possible. The valves, themselves, are of simple construction, as shown, and are of uniform dimensions so that two of them can be interchanged at will; or the expansive rings 35 be replaced; etc.

Disposed at any suitable point in the channel 32, I may employ a spring-controlled check-valve 48 adapted to be actuated by the compressed mixture to open the same when the mixture moves through the channel in the direction of the explosion-chamber, and adapted to be seated by the motive fluid after ignition has occurred, should the mixture be prematurely ignited in the explosion-chamber and should the valve 43 still be open, thereby preventing a return of said motive fluid toward the auxiliary-chamber 18. In this way, I provide precautionary means to protect the mixture which is stored in the auxiliary-chamber 18 and, thus, preclude the danger of any firing of said mixture either in the channel 32 below the valve or in the auxiliary-chamber 18.

Thereby, I am enabled to cause a delivery of pure mixture from the auxiliary chamber 18 into the explosion-chamber without regard to whether there may have been a false firing therein, or not. In other words, if for any reason the valve 43 does not work timely or becomes inoperative, the check-valve 48 will hold the motive fluid in the explosion-chamber and ready to effect a work-stroke of the piston. This is the particular function of this check-valve 48.

In the event that the valve 43 should be open while exhaust is occurring and the piston is rising, the check-valve 48 will prevent the passage of any of the burned mixture into the channel 32 and, thus, back into the storage-chamber 18. The moment the exhaust pressure falls below that of the mixture passing up through the channel 32, assuming that the valve 43 is open, such pressure will open the valve 48 and thereby permit proper delivery of the mixture into the explosion-chamber and the forcing out of the chamber of any burned gases that may remain owing to atmospheric or muffler pressure. The scavenging of the explosion-chamber is thus not only facilitated but practically made perfect.

On the side of the cylinder opposite to the valve 43, I provide an exhaust-port 49 controlled by a valve 50 of form similar to valves 33 and 43. A valve-stem 51 connects with the valve 50 and has pivoted at its lower end a link 52 jointed to a standard 53 on the cylinder. The link 52 carries a roller 54 adapted to traverse a cam-groove 55 formed on the face of the disk 40 opposite to the cam-grooves 39 and 47. It will thus be seen that one disk serves as a device common to the valves 33 and 43 on the one side, and that a second disk serves as an operating-device for the exhaust controlling-valve. Where a plurality of cylinders are employed, there will be one disk in excess of the number of cylinders, so that each intermediate disk serves as a device for operating the valves 33 and 43 on the one cylinder, and to operate the exhaust controlling-valve on the next-adjacent cylinder; the cam-grooves formed therein are so arranged that the proper relative timing of operation of the valves is effected. The feature of providing a cam-groove, having two walls, insures the positive movement of the valve at the proper moment and in a proper manner, thus making certain the timely delivery of the mixture into the explosion-chamber, the exhaust, etc.

As usual, the crank-shaft 23 is provided with a balance-wheel 56 which preferably will be of reduced dimensions. By eliminating the usual suction and compression-strokes of the piston, the balance-wheel does not have to be employed to produce sufficient momentum of the crank-shaft, as in the

usual two and four-cycle engines, to operate the crank-shaft properly; and, moreover, as premature ignition and back-firing in my engine facilitate rather than retard the operation of the piston, the dimensions of the balance-wheel may, for this further reason, be of reduced size.

As shown particularly in Fig. 5, and in part in Figs. 2 to 4, I provide a conduit 57 to conduct the mixture from the carbureter as usual. In this instance, the conduit 57 is tapped to feed the mixture into each of the cylinders. Valves 57^a control passage through conduit 57, etc., as usual.

Similarly, an exhaust-conduit 58, common to the several cylinders, is provided.

Operation.—The cycle of operation of this engine will be apparent. It may be stated, however, that, assuming that the piston is in a position to begin its work-stroke and that the crank is then at upper dead-center, ignition is started to effect an explosion of mixture which has already been admitted into the explosion-chamber. The ignition can occur or be effected without regard to what may be the position of the piston on its work-stroke. During this work-stroke, compression of a previously-admitted mixture into the compression-chamber 26 is effected, and this compression takes place during the entire work-stroke of the piston. Just in advance of the completion of the piston's work-stroke, the exhaust-valve is opened (through the operation of its valve-operating mechanism already described) and exhaust will then take place during the movement of the crank through its lower dead-center position and until the crank has arrived at approximately ten or fifteen degrees of its upper dead-center, whereupon the exhaust-valve closes and the cylinder will then be thoroughly scavenged. Practically simultaneous with the closing of this valve 50, the inlet valve 43 is, by its operating mechanism, suddenly opened to admit into the explosion-chamber the mixture held under pressure in the channel 32. This flow of mixture continues until the crank has arrived at, or approximately at, its upper dead-center, whereupon the valve 43 is suddenly closed by its operating-mechanism.

Ignition then occurs according to the timing of the ignition device, and the piston again performs its work-stroke in the manner already described. During the work-stroke of the piston and while it is effecting a compression of the mixture in the compression-cylinder 26, the valve 33 will have been opened by its aforementioned operating-mechanism. Then, while the piston is continuing its down-stroke and while the crank is in proximity to its lower dead-center position, the valve 33 will be closed. The valve 33 then being closed and similarly the valve 43 being closed, the compressed mixture is

held in said storage-chamber 18 and channel 32 until the inlet valve 43 is opened to permit the mixture to be delivered into the explosion-chamber at a predetermined time, and as already described. Any compressed mixture that may remain in the compression-chamber 26 will, being compressed, act as a resilient power that may be utilized to accelerate the return of the piston during the commencement of its up-stroke. A continuation of the up-stroke of the piston will have created a vacuum in the compression-chamber 26 and thus automatically opened the carbureter check-valve 57, and permitted an inflow of the mixture into said compression-chamber 26 and this inflow continues until the vacuum has been eliminated, even though the piston may have begun its work-stroke and the crank passed its upper dead-center position. Thus, it will be seen that in a very rapid operation of the engine, there being no mechanically operated valve employed to cut off this inflow of the mixture when the piston and crank have arrived at dead-center, this vacuum will continue and the flow of the mixture will continue until the vacuum has been eliminated. This cycle of operation will be made quite clear by reference to Fig. 9, which shows diagrammatically the approximate periods of ignition operation and inactivity of the valves during the work and exhaust-strokes, respectively, of the piston.

As already stated, the enlarged portions 35 24 of the crank-shaft 23 serve the dual function of aiding in a compression of the mixture in the compression-chamber and, also, to counterbalance the crank-shaft. They may, also, operate somewhat to effect a certain amount of distribution of the lubricant that may remain in the lower portion of the chamber.

The oil storage-chamber 17 constitutes a source of supply of lubricant, and from this chamber a series of pipes may lead to various parts of the engine for the distribution of the lubricant to such parts. For instance, the lubricant may, by these means, be supplied to the valves, as, for instance, shown in Fig. 1, where an oil-duct 59 is formed in the wall of the cap-portion and which communicates with the port controlled by the valve 43. Any other form of lubricating distributor may be employed, if desired. The oil-chamber 17 is provided with a filling-orifice 60.

So far as I am advised, the valve-system which I have herein disclosed is new for internal combustion engines. While I have herein illustrated the same as adapted to the two-cycle type of engine, it will be understood that it is equally applicable to the four-cycle type. The only modification that might be necessary to adapt the same thereto would be in predetermining a differ-

ence in timing of the relative operation of the several valves; and this could be effected either by an auxiliary cam-shaft, or by employing a gear or gears mounted directly on the crank-shaft and meshing with other gearing in the usual 2-to-1 order, as well understood in the art. The valves of the system are, as shown, located on the outside of the cylinder, are practically noiseless, and are preferably located so that their axes of rotation are at right angles to the piston-chamber.

As a result of practical use and observation of present-day two and four-cycle engines, I have observed that they are open to serious objections and include defects which it is the object of my invention to overcome. Among these, may be mentioned the fact that the structures of these engines are, for the most part, very complicated and include a great many parts, giving to the entire engine great weight; moreover, the valves are inaccessible, and are also defective, first, because they are placed inside of the motor and are not positively operated but are dependent upon springs or one-way operating cams and the like; secondly, they cannot conveniently, if at all, be lubricated; and, thirdly, the operation of these valves is not always reliable and cannot be predetermined to produce the highest efficiency; furthermore, due to the high speed, resulting in an increase in centrifugal force, rapid wear of the bearings, etc., necessarily follows; furthermore, the high speed at which the engine must be run to result even with a fair degree of efficiency releases a large portion of the heat-units, and these heat-units constitute power so that loss of the heat-units means the loss of power; furthermore, back and false-firing are frequent incidents, with attendant dangers and serious results; furthermore, if, for any reason, the spark is untimely effected, resulting in back-firing, firing back into the carbureter, with attendant injury to the valves through which the fired mixture passes, naturally results, with consequent consumption of the mixture back as far as the carbureter; and, finally, where a sequence of suction, compression and exhaust-strokes have to be performed, there is necessarily a great waste of power incident to the operation of the engine to produce these ineffective strokes, etc.

A comparison of my engine with these present-day motors will make apparent the fact that I have overcome these and other defects and objections, because, in the first place, I eliminate the sequence of suction, compression and exhaust-strokes between each effective work-stroke; and, even, during the up-stroke of the piston to effect exhaust, I provide an instrumentality for aiding the movement of the piston at the commencement of its upward stroke, so that

utilization of comparatively little power to effect suction and exhaust-strokes is required. The work-stroke which is performed in my engine is free to produce a maximum of power because the power-strokes occur with each revolution and, moreover, the cylinder is always thoroughly scavenged. Where two cylinders are employed, the power-strokes are effected every half revolution. Where three cylinders are embodied, the power-strokes are effected every third of a revolution. Where four cylinders are coupled, there would be a power-stroke at every quarter revolution.

15 The construction of my engine is such, and it operates in a manner, tending to conserve the heat-units, and, thus, the loss of power. Moreover, false and back-firing are entirely eliminated, because premature ignition in the explosion-chamber is on the up-stroke of the piston and any advancing of the operation of the sparkler can work no injuries, because, if ignition does take place during the up-stroke of the piston, such can only occur while exhaust is being effected of the consumed charge, making it "fool-proof", so to speak. If ignition should take place directly after the exhaust-port is closed and just at the moment of the introduction 30 into the explosion-chamber of a fresh mixture, there simply results what is the equivalent of a normal work-stroke when the spark is advanced. It is to be understood that, as the mixture is not normally introduced until 35 just before the piston has arrived at the explosion-chamber end of the cylinder and when the crank is nearly at its upper dead-center position, if the mixture should then be ignited, the piston would then be actuated 40 in its normal direction; and, if the regulating valve had not been allowed sufficient time to close (though the opening and closing of it is effected very rapidly), the check-valve 48 will prevent the prematurely-ignited mixture from reaching back to the mixture-chamber and the channel. Thus, 45 false-firing and premature ignition are, in my engine, not matters of danger nor disadvantages.

50 Another feature of the construction, as already pointed out, is that the valves are positively actuated and are not dependent upon springs which are always unreliable; moreover, the valves are constantly lubricated to reduce wear thereon; and, moreover, the thrust on the valve, at the time of the explosion, is endwise, and such thrust is imposed upon the exposed surface of the end of the valve and the resilient washer back 55 of the same, and in this way, there is no wear upon the valve or its bearing. The parts are comparatively few in number and are of simple construction and make the machine relatively light. In most of the present-day two-cycle types of engines, the pis-

ton is utilized to perform a double function, to-wit, it acts as a piston and, also, as a valve or double valve, thereby reducing its efficiency for either function. In my engine, in the two-cycle type, wherein a full suction, 70 a full compression, a full work and exhaust-strokes are performed, I secure all the advantages of the four-cycle and, in addition, generate power at every revolution plus the advantage of high compression and plus the 75 advantage secured by utilizing the force of the compressed mixture in the compression-chamber to aid in effecting the up-stroke of the piston. I have as many work-strokes at six hundred revolutions of the shaft as does 80 the four-cycle type of engine at twelve hundred revolutions of the shaft; and, also, have more power, because the piston is not racing away from the expanding force as in the four-cycle engine; and the time permitted to increase the heat energy before exhaust is doubled. In consequence of these features, the engine is necessarily capable of high speed; and, even if run at low speed, it is capable of generating great power. 85 Moreover, the described valve-mechanism makes the engine non-reversing; that is to say, the valves are so timed to operate that the exhaust is open during the up-stroke of the piston and until the inlet opens; hence, if, for any reason, the mixture flowing through inlet should ignite prematurely (when, for instance, the motor had not acquired sufficient momentum to carry the piston through its complete cycle) the tendency would be to force the piston back or downward and cause the crank to turn in the wrong direction. But the instant this occurs, the exhaust-port opens and this will relieve the pressure on the head of the piston and because of the compression in the lower chamber, the piston will come to a stop on its first cycle. It is recognized that, in a 90 four-cycle engine, a charge may ignite during the suction-stroke of the piston, and, if the inlet-valve be open, the piston will be driven forward. Then, a back-fire takes place to the carburetor and this sometimes results in a firing of the carburetor. If the piston then rises for the compression-stroke 95 (while all valves are closed) the rapidly expanding ignited gas which will have remained in the cylinder will rack the motor and bring it to a stop. If the charge pre-ignites during the compression-stroke of the 100 piston, the latter will reverse and operate for a work-stroke and, owing to the fact that both valves may be closed, the crank-shaft will move in the wrong direction. Such an operation cannot occur in my motor 105 for the reasons mentioned.

110 It is to be understood that, though I have described the invention with considerable detail, I do not limit myself to such details nor to the particular aggroupment thereof, 115

nor to the particular form of the parts of the structure.

Having thus described my invention, its construction and the preferred manner of operating it, what I claim and desire to secure by Letters-Patent is:

1. An internal combustion engine including in combination, a cylinder provided with a channel in its wall, a piston working in the cylinder, an explosion-chamber located in the cylinder at one side of the piston, a compression-chamber also located in the cylinder at the opposite side of the piston, and an auxiliary-chamber disposed adjacent to the compression-chamber and communicating therewith, said channel establishing communication between said auxiliary-chamber and the explosion-chamber, a rotatable valve distinct from the piston for opening and closing said channel, and a single means for actuating said valve in two directions whereby a firing-mixture may be intermittently introduced into the explosion-chamber from the auxiliary-chamber.

2. An internal combustion engine including in combination, a cylinder provided with a channel in its wall, a piston working in the cylinder, an explosion-chamber located in the cylinder at one side of the piston, a compression-chamber also located in the cylinder at the opposite side of the piston, an auxiliary-chamber disposed adjacent to the compression-chamber and communicating therewith, said channel establishing communication between said auxiliary-chamber and the explosion-chamber, a valve movable in two directions for controlling the passage of the mixture from the compression-chamber into said auxiliary-chamber and a single means for actuating said valve in both directions.

3. An internal combustion engine including in combination, a cylinder provided with a channel in its wall, a piston working in the cylinder, an explosion-chamber located in the cylinder at one side of the piston, a compression-chamber also located in the cylinder at the opposite side of the piston, an auxiliary-chamber disposed adjacent to the compression-chamber and communicating therewith, said channel establishing communication between said auxiliary-chamber and the explosion-chamber, a valve movable alternately in two directions for controlling the passage of the mixture from the compression-chamber into said auxiliary-chamber, a valve movable in two directions for controlling the passage of the mixture from said auxiliary-chamber to the explosion-chamber and a single means for actuating said last-mentioned valve in both directions.

4. An internal combustion engine including in combination, a cylinder, a piston working therein, an explosion-chamber lo-

cated at one side of said piston, a compression-chamber located at the opposite side of said piston, an auxiliary-chamber arranged in proximity to the compression-chamber, a port between said compression-chamber and said auxiliary-chamber, means for controlling the passage of fluid through said port, a channel formed in the wall of the cylinder between said auxiliary-chamber and said explosion-chamber, mechanism independent of said controlling means and adapted to control the passage of the mixture through said channel, and a pressure-operated valve independent of said mechanism for controlling passage of fluid through the channel at least in one direction.

5. An internal combustion engine including in combination, a cylinder, a piston working therein, an explosion-chamber located at one side of said piston and provided in its ignition end with inlet and exhaust ports, a compression-chamber located at the opposite side of said piston, an auxiliary-chamber arranged in proximity to the compression-chamber, a port between said compression-chamber and said auxiliary-chamber, means for controlling the passage of fluid through said port, a channel formed in the wall of the cylinder between said auxiliary-chamber and said explosion-chamber, independent valves for said inlet and exhaust ports operable in two directions in predetermined relation, and a single means for each valve adapted to actuate the same in both directions.

6. In an engine, a cylinder, a crank-shaft therein, a piston connected to the shaft, a firing-chamber formed in the cylinder and provided with an inlet port and with an exhaust-port for exhausting the contents of the chamber during the completion of the work-stroke of the piston and until completion of the exhaust-stroke thereof, a storage-chamber for containing a mixture, and means associated with the firing-chamber for holding the mixture in the storage-chamber under pressure and to release the same into the firing-chamber slightly in advance of the closing of the exhaust-port to completely scavenge the firing-chamber and to operate the piston when the mixture is ignited.

7. In an engine, a cylinder, a crank-shaft therein, a piston connected to the shaft, firing and compression chambers formed in the cylinder and provided with inlet ports, the firing chamber being also provided with an exhaust port for exhausting the contents of the chamber during the completion of the work-stroke of the piston and until completion of the exhaust-stroke thereof, a storage-chamber for containing a mixture, and means associated with the firing chamber for holding the mixture in the storage-chamber under pressure and to release the

same into the firing-chamber slightly in advance of the closing of the exhaust-port to completely scavenge the firing-chamber and to operate the piston when the mixture is ignited and including a shaft-operated valve for controlling one of said ports.

8. An internal combustion engine including in combination, a cylinder provided with a single chamber at its one end and a plurality of chambers at the opposite end, a piston working in said cylinder intermediate said single and plurality of chambers, one of said chambers being an explosion-chamber, another thereof a compression-chamber, and a third a storage-chamber, a channel extending from said storage-chamber to said explosion-chamber, a check-valve operating in said channel to prevent the passage of motive fluid through said channel and into the storage-chamber, and a second valve operating in said channel to control the passage of mixture through said channel independently of the piston in either direction.

25. An internal combustion engine including in combination, a cylinder provided with a single chamber at its one end and a plurality of chambers at the opposite end, a piston working in said cylinder intermediate said single and plurality of chambers, one of said chambers being an explosion-chamber, another thereof a compression-chamber, and a third a storage-chamber, a channel extending from said storage-chamber to said explosion-chamber, a check-valve operating in said channel to prevent the passage of motive fluid through said channel and into the storage-chamber, a second valve operating in said channel independently of 40 the piston to control the passage of mixture through said channel in either direction, and a third valve to control the passage of the mixture from the compression-chamber into the storage-chamber and operating to prevent the return of motive-fluid into the compression-chamber.

10. An internal combustion engine including in combination, a cylinder provided with a single chamber at its one end and a plurality of chambers at the opposite end, a piston working in said cylinder intermediate said single and plurality of chambers, one of said chambers being an explosion-chamber, another thereof a compression-chamber, and a third a storage-chamber, a channel extending from said storage-chamber to said explosion-chamber, a check-valve operating in said channel to prevent the passage of motive fluid through said channel and into the storage-chamber, a second valve operating in said channel to control the passage of mixture through said channel in either direction, a third valve to control the passage of the mixture from the compression-chamber into the storage-chamber and

operating to prevent the return of the mixture into the compression-chamber, and a valve for exhausting from the explosion-chamber.

11. An internal combustion engine including in combination, a cylinder provided with a single chamber at its one end and a plurality of chambers at the opposite end, a piston working in said cylinder intermediate said single and plurality of chambers, one of said chambers being an explosion-chamber, another thereof a compression-chamber, and a third a storage-chamber, a channel extending from said storage-chamber to said explosion-chamber, a check-valve operating in said channel to prevent the passage of motive fluid through said channel and into the storage-chamber, a second valve operating in said channel to control the passage of mixture through said channel in either direction, a third valve to control the passage of the mixture from the compression-chamber into the storage-chamber and operating to prevent the return of the mixture into the compression-chamber, a valve for exhausting from the explosion-chamber, a crank-shaft connecting with said piston, and with which a plurality of said valves connect and by which they are positively actuated.

12. An internal combustion engine including in combination, a cylinder provided with a single chamber at its one end and a plurality of chambers at the opposite end, a piston working in said cylinder intermediate said single and plurality of chambers, one of said chambers being an explosion-chamber, another thereof a compression-chamber, and a third a storage-chamber, a channel extending from said storage-chamber to said explosion-chamber, a check-valve operating in said channel to prevent the passage of mixture through said channel and into the storage-chamber, a second valve operating in said channel to control the passage of mixture through said channel in either direction, a third valve to control the passage of the mixture from the compression-chamber into the storage-chamber and operating to prevent the return of the mixture into the compression-chamber, a valve for exhausting from the explosion-chamber, a crank-shaft connecting with said piston, and with which a plurality of said valves connect and by which they are positively actuated in both directions.

13. An internal combustion engine including in combination, a plurality of cylinders arranged in juxtaposition, each cylinder being provided in its wall with a channel, a piston adapted to be reciprocated in the cylinder, an explosion-chamber at one side of the piston, a compression-chamber at the opposite side thereof, said channel establishing communication between the com-

pression-chamber and the explosion-chamber, a valve for controlling the passage of mixture through said channel, a crank-shaft in the base of said cylinder, a plurality of

5 cam-disks fast on said shaft and each provided with a cam groove, connections between the channel-controlling valves and the cam-grooves, each connection having one end adapted to traverse the cam-groove in
10 the disk and thereby be positively actuated in a plurality of directions and in predetermined relation to the actuation of an adjacent valve.

14. An internal combustion engine including in combination, a plurality of cylinders arranged in juxtaposition, each cylinder being provided in its wall with a channel, a piston adapted to be reciprocated in the cylinder, an explosion-chamber at one side of
20 the piston, a compression-chamber at the opposite side thereof, said channel establishing communication between the compression-chamber and the explosion-chamber, a valve for controlling the passage of
25 mixture through said channel, a crank-shaft in the base of said cylinder, a plurality of cam-disks fast on said shaft, some of which are provided with a plurality of cam-grooves, connections between the channel-controlling valves and the cam-grooves, each connection having one end adapted to traverse its respective cam-groove in the disk and thereby be positively actuated in a plurality of directions and in predetermined
30 relation to the actuation of an adjacent valve, said cylinder being provided with an exhaust-port, a valve for controlling the exhaust-port, a connection attached to the valve at one end and having its other end
35 adapted to traverse one of the grooves in the cam-disk.

15. An internal combustion engine including in combination, a plurality of cylinders arranged in juxtaposition, each cylinder being provided in its wall with a channel, a piston adapted to be reciprocated in the cylinder, an explosion-chamber at one side of the piston, a compression-chamber at the opposite side thereof, said channel establishing communication between the compression-chamber and the explosion-chamber, a valve for controlling the passage of mixture through said channel, a crank-shaft in the base of said cylinder, a plurality of cam-disks fast on said shaft, some of which are provided with a plurality of cam-grooves, connections between the channel-controlling valves and the cam-grooves, each connection having one end adapted to traverse its respective cam-groove in the disk and thereby be positively actuated in a plurality of directions and in predetermined relation to the actuation of an adjacent valve, said cylinder being provided with an exhaust-port, a valve for controlling the exhaust-port, a

connection attached to the valve at one end and having its other end adapted to traverse one of the grooves in the cam-disk, said crank-shaft being elongated and common to the pistons in the several cylinders.

16. An internal combustion engine, a cylinder, a piston reciprocable therein, a crank-shaft journaled in the cylinder and operatively connected to the piston, an explosion-chamber at one side of the piston, a compression-chamber at the opposite side of the piston, an auxiliary-storage-chamber in proximity to the compression-chamber, a channel in the wall of the cylinder and communicating with the storage and explosion-chambers, a valve for controlling the passage of fluid from the compression-chamber into the storage-chamber, and a valve for controlling the passage of the fluid through said channel, said cylinder being provided with an exhaust-port and a valve therefor, said crank-shaft carrying cam-disks provided with a plurality of cam-grooves, and valve-stems working in said grooves and communicating with said valves, and operated by said cam-disks at a predetermined time to open or close the several valves relatively.

17. An internal combustion engine including in combination, a cylinder, a piston reciprocable therein, an explosion-chamber located at one side of the piston, a compression-chamber located at the opposite side of said piston, an auxiliary-chamber arranged in proximity to said compression-chamber, and provided with a port communicating with said compression-chamber, a valve adapted to control the passage of compressed mixture from said compression-chamber into said auxiliary-chamber and operable to close the port before the entire contents of the compression have passed into the auxiliary-chamber in order to leave in the compression-chamber a portion of the compressed mixture, such remaining compressed mixture then being operative to aid the piston in its up-stroke.

18. An internal combustion engine including in combination, a cylinder, an explosion-chamber arranged at one end thereof, a compression-chamber arranged at the opposite end thereof, an auxiliary-chamber arranged in proximity to the compression-chamber, a piston adapted to reciprocate in the cylinder between the explosion and compression-chambers to compress mixture in the compression-chamber and to force a portion thereof into the auxiliary-chamber, means for trapping a portion of the mixture within the compression-chamber, the portion of said compressed mixture remaining in the compression-chamber operating upon the underside of the piston to aid, at the commencement of the up-stroke of the piston, to return it toward starting position.

19. An internal combustion engine including in combination, a cylinder, an explosion-chamber arranged at one end thereof, a compression-chamber arranged at the opposite end thereof, an auxiliary-chamber arranged in proximity to the compression-chamber of relatively smaller dimensions, a piston adapted to reciprocate in the cylinder between the explosion and compression-chambers to compress mixture in the compression-chamber and to force a portion thereof into the auxiliary-chamber, means for trapping a portion of the mixture within the compression-chamber, the portion of said compressed mixture remaining in the compression-chamber operating upon the underside of the piston to aid, at the commencement of the up-stroke of the piston, to return it toward starting position.
20. An internal combustion engine including in combination, a cylinder, an explosion-chamber arranged at one end thereof, a compression-chamber arranged at the opposite end thereof, an auxiliary-chamber arranged in proximity to the compression-chamber, a piston adapted to reciprocate in the cylinder between the explosion and compression-chambers to compress mixture in the compression-chamber and to force a portion thereof into the auxiliary-chamber, means for trapping a portion of the mixture within the compression-chamber, the portion of said compressed mixture remaining in the compression-chamber operating upon the underside of the piston to aid, at the commencement of the up-stroke of the piston, to return it toward starting position, and a valve for trapping the compressed mixture in the auxiliary-chamber.
21. An internal combustion engine, including in combination a channeled cylinder provided with an explosion-chamber at one end, a compression-chamber at the opposite end, an auxiliary-chamber in communication relation to the compression-chamber, means for controlling the mixture from the compression-chamber to the auxiliary-chamber, means for controlling the compressed mixture through the channeled portion of the cylinder, and a piston reciprocable within the cylinder, and adapted to compress a mixture in the compression-chamber and to force a portion of said chamber's contents into the auxiliary-chamber, means for trapping a portion of the mixture within the compression-chamber, the portion of said compressed mixture remaining in the compression-chamber operating upon the underside of the piston to aid, at the commencement of the up-stroke of the piston, to return it toward starting position.
22. An internal combustion engine including a cylinder and a crank-case, a piston reciprocable in the cylinder, an explosion chamber formed in the cylinder, a compression and an auxiliary-chamber formed in the crank-case, said auxiliary-chamber provided with ports communicating with the explosion and compression-chambers, and means remote from the piston and operable in predetermined relation thereto for controlling the passage through said ports.
23. An internal combustion engine including a cylinder and a crank-case, a piston reciprocable in the cylinder, an explosion chamber formed in the cylinder, a compression and an auxiliary-chamber formed in the crank-case, said auxiliary-chamber provided with ports communicating with the explosion and compression-chambers, and means remote from the piston and operable in predetermined relation thereto for intermittently opening the passage through said ports.
24. An engine including a cylinder, explosion and compression chambers therein, a piston reciprocable within the cylinder and operable to compress a gaseous mixture in one of said chambers and driven in one direction by an ignited gas in the explosion chamber to compress a body of gaseous mixture in the compression chamber, means for controlling the ignited gas in the explosion chamber while the piston is moving to compress the gaseous mixture in the compression chamber, means for controlling the outflow of the compressed mixture from the compression chamber and operable to release from the compression chamber a portion of such mixture for utilization of the same in the explosion chamber, and means for conveying such released mixture from the compression chamber to the explosion chamber.
